UNITED STATES PATENT OFFICE

GARNET W. MCKEE, OF ROCKFORD, ILLINOIS

THERMOSTATIC CONTROL

Application filed August 4, 1930. Serial No. 472,836.

The present invention relates to improvements in thermostatic controls, and has particular reference to a novel control device for controlling the flow of gas to a burner for a water heater in accordance with the temperature of the water.

If hard water is heated to a temperature above 150° F., an excessive amount of lime will be deposited in the water lines. One of the objects of the present invention therefore resides in the provision of a new and improved thermostatic control device in which the change in volume in passing from a solid to a liquid state and vice versa of a substance having a melting point slightly under 150° F. is utilized to close and open a valve.

Another object is to provide novel means for seating the valve with a balanced pressure so as to obtain a tight fit.

20 A further object resides in the provision of a novel thermostatic control device which is simple, compact and inexpensive in construction, and in which the operative parts are sealed out of contact with the water.

25 Other objects and advantages will become apparent as the description proceeds.

Referring more particularly to the drawing, Figure 1 is a bottom view of a thermostatic control device embodying the features 30 of my invention.

Fig. 2 is a fragmentary side view, partially sectioned in a vertical plane along line 2—2 of Fig. 1.

35 Fig. 3 is a side elevational view of a modified form of the invention.

Fig. 4 is a vertical sectional view taken along line 4—4 of Fig. 3.

While the invention is susceptible of various modifications and alternative constructions, I have shown in the drawing and will herein describe in detail the preferred embodiment, but it is to be understood that I do not thereby intend to limit the invention to the specific form disclosed, but intend to cover all modifications and alternative constructions falling within the spirit and scope of the invention as expressed in the appended claims.

50 Referring more particularly to the drawing, the thermostatic control device shown in

Figs. 1 and 2 comprises a suitable base 5 preferably in the form of a plate. A cover 6 is removably secured on the base 5, and constitutes therewith a casing, the interior of which defines a valve chamber 7.

55 Formed on the underside of the base 5 are two tubular enlargements defining fluid passages 8 and 9 opening in spaced relation through the base into the chamber 7. Of the passages 8 and 9, one is the inlet passage 60 adapted to be connected to a suitable source of fluid supply (not shown), and the other is the discharge passage adapted to be connected to a burner supply line (not shown).

65 A valve member 10 is mounted to seat over one of the passages, for example the passage 9. It will be understood that the valve may be utilized to control the fuel mixture, or either of its constituents, namely fuel gas or air.

70 While the invention is particularly intended to control the supply of fuel mixture to a burner (not shown) for a water heater (not shown) in accordance with the temperature of the water, and is herein described in its adaptation to such use, it will be evident that the invention in various of its aspects is not limited to such use, but may be utilized to control the flow of any fluid in accordance with predetermined temperature conditions.

75 The valve member 10 is responsive to a suitable pressurestat. In the present instance, the pressurestat comprises a tube 11 closed and tapered at one end. The other end of the tube 11 is sealed with a pressure responsive member, such as a diaphragm 12. Preferably, the peripheral margin of the diaphragm 12 is disposed against a shoulder 13, and is secured in place by a ring 14 soldered to the tube 11.

80 The tube 11 is formed intermediate its ends with external threads 15 adapted to be threaded into one wall of the water chamber (not shown) with the tapered end in contact with the water. Preferably, the other end of the tube 11 is formed with an annular flange 16 threaded onto a cylindrical boss 17 on the underside of the base 10, and serving to clamp the ring 14 securely against the end of the boss. A recess 18 formed in the end of

the boss 17 permits free outward flexure of the diaphragm 12. The diaphragm 12 thus is fully enclosed, and sealed out of contact with water.

5 The tube 11 is filled with a suitable substance adapted to go through a change of state at the desired temperature. In the present instance, paraffin 19, melting at 144° F., is used. In filling the tube 11, the diaphragm 12 is held against flexure outwardly into the recess 18, and the paraffin 19 is introduced through an opening 20 in the tip of the tube. When the tube 11 is filled with solid paraffin, the opening 20 is closed by 10 means of a screw plug 21. It will be evident that the paraffin upon melting will flex the diaphragm 12 outwardly, and upon solidifying will permit the diaphragm to return to its innermost position.

20 Extending slidably through a bore 22 in the boss 17 from the recess 18 into the chamber 7 is a plunger 23. The end of the plunger 23 in the recess 18 is provided with an enlarged head 24 resting on the diaphragm 12.

25 Pivotally mounted intermediate its ends in a bracket 25 on the base 5 is a lever 26 one arm 27 of which carries an adjustable set screw 28 engaging the end of the plunger 23 in the chamber 7.

30 A coiled compression spring 29 interposed between the base 5 and the other arm 30 of the lever tends to maintain the screw 28 in contact with the plunger 23 and the latter in contact with the diaphragm 12. Preferably, one end of the spring 29 has a plurality of 35 tight coils 31 threaded onto a screw 32 carried by the arm 30. Thus, the spring 29 is held in place on the arm 30, and cannot work loose.

40 The free end of the arm 30 of the lever 26 carries the valve member 10. Preferably screws 33 and 34 are provided respectively on the arm 30 and the valve member 10. A coiled spring 35 is provided with a plurality of tight coils 36 and 37 on its opposite ends 45 threaded respectively onto the screws 33 and 34 to secure the valve member 10 yieldingly to the arm 30. Thus, the valve member 10 is adapted to be seated with a balanced pressure. The pressure may be varied by 50 adjusting the set screw 28 to adjust the extent of movement of the valve member 10 between open and closed positions.

55 In operation, when the temperature exceeds 144° F., the paraffin 19 will melt and expand against the diaphragm 12. The movement of the diaphragm 12 is imparted through the plunger 23, the lever 26 and the spring 35 to the valve member 10 to close the 60 passage 9. The valve member 10 seats squarely with a balanced pressure. When the temperature drops below 144° F., the paraffin 19 will solidify, whereupon the spring 29 will cause the valve member 10 to 65 open.

Referring now to Figs. 3 and 4, the modified form of the invention comprises a valve casing 38 formed with inlet and discharge passages 39 and 40 and with a valve seat 41 intermediate said passages. A valve member 42 is mounted for movement into and out of engagement with the valve seat 41.

70 Mounted in one side of the casing 38 is an elongated sleeve 43 which is formed intermediate its ends with threads 44 adapted to be threaded into one wall of the water chamber (not shown). Secured to the free end of the sleeve 43 is a tube 45, with a diaphragm 46 interposed between the connecting ends of the sleeve and the tube. The tube 45 is 75 tapered, and is filled with paraffin 47 which is introduced through an opening 48 in the free end normally closed by a screw plug 49.

80 In the present instance, a direct acting connection is provided between the valve member 42 and the diaphragm 46. This connection comprises a plunger 50 reciprocable in the sleeve 43, with one end supporting the valve member 42 and the other end bearing 85 against the diaphragm. A coiled spring 51 encircling the plunger 50, and abutting at its ends against an inner peripheral flange 52 in the sleeve 43 and a peripheral flange 53 on the plunger tends to urge the latter against the diaphragm 46 and the valve member 42 90 away from the seat 41.

95 A yieldable connection is provided between the valve member 42 and the plunger 50. To this end, the valve member 42 is formed in one side with an axial bore 54 slidably receiving the adjacent end of the plunger 50. A bolt 55 extends through the valve member 42 into adjustable threaded engagement with the end of the plunger 50, and has a head 56 100 limiting the outward movement of the valve member. A coiled spring 57 encircling the plunger 50 and abutting at its ends against the valve member and a peripheral shoulder 58 on the plunger tends to move the valve member outwardly against the head 56.

105 The plunger 50 is formed with a diametrical bore 59 adapted for the temporary reception of a pin (not shown) for holding the plunger away from the diaphragm 46 while the latter is being soldered in place against the shoulder formed for the purpose in the tube 45. After soldering the diaphragm 46 securely in place, the described pin is removed and the spring 51 then forces the plunger 50 against the diaphragm 46 when 110 introducing the paraffin 47 to the tube.

115 I claim as my invention:—

120 1. A control device comprising, in combination, a passage, a valve controlling said passage, a closed tapered member having a flexible wall at its large end, paraffin completely filling said member and sealed therein, said wall being responsive to changes in volume of said paraffin, and means operatively connecting said wall to said valve.

2. In a control device, in combination, a casing defining a valve passage, a valve actuator mounted in said casing, a valve for controlling said passage, said actuator and said valve being provided respectively with oppositely disposed screws, and an open coiled connecting spring having a plurality of tight coils on each end threaded respectively onto said screws.
3. In a control device, in combination, a casing defining a valve passage, a valve actuator mounted in said casing, a valve for controlling said passage, said actuator being provided with a fixed screw, and an open coiled spring connected to said valve and having a plurality of tight coils on one end threaded onto said screw.
4. A control device comprising, in combination, a casing formed with a passage, a valve for controlling said passage, a hollow conical member having a yieldable wall closing its large end and secured at said end to said casing, the small end of said member being free, wax completely filling said member and sealed therein, and means for transmitting the movements of said wall to said valve.
5. A control device comprising, in combination, a casing having a passage, a valve for controlling said passage, a hollow member having a chamber of gradually decreasing cross-sectional area and having a yieldable wall closing the large end of said chamber, said member being secured to said casing, a substance adapted to undergo a change in volume upon being subjected to varying temperatures, said substance being sealed in said member, and means for transmitting the movements of said wall to said valve.
6. A control device comprising, in combination, a casing having a passage, a valve for controlling said passage, a conical tube having a flexible wall closing its large end and secured at its large end of said casing, the small end of said tube being free, wax sealed within said tube, and means for transmitting the movements of said wall to said valve, said means including spring means tending to cause said wall to follow any reduction in volume of said wax.
7. A control device comprising, in combination, a valve casing formed with a passage, a valve for controlling said passage, an elongated sleeve rigid with said casing, a conical tube with its large end threaded onto the free end of said sleeve, a flexible diaphragm secured between said tube and the free end of said sleeve and constituting a wall closing the large inner end of said tube, the small outer end of said tube being free, wax adapted to undergo a change in state with an attendant change in volume at a predetermined temperature, said wax filling and being sealed in said tube, and means for transmitting the movements of said wall to said valve.
8. A control device comprising, in combination, a casing formed with a passage, a valve controlling said passage, an elongated sleeve rigid with said casing, a conical tube secured at its large end to the free outer end of said sleeve, the small end of said tube being free, a removable plug closing said small end of said tube, a flexible wall closing the large inner end of said tube, a plunger slideable longitudinally in said sleeve and bearing at one end against said wall, and means operatively connecting the other end of said plunger to said valve.
- In testimony whereof, I have hereunto affixed my signature.
